UNITED STATES PATENT OFFICE.

ALBERT J. HOLT, OF MUSKOGEE, OKLAHOMA.

FLOATING COVER FOR OIL TANKS.

Application filed May 13, 1925. Serial No. 30,021.

This invention relates to oil tanks and one object of the invention is to provide an improved cover which is so constructed that it may be slidably placed in an oil tank and 5 float upon the surface of oil contained in the tank, the cover not only serving to prevent excessive loss of oil by evaporation but also serving to prevent danger of the oil being set on fire.

10 Another object of the invention is to so construct the floating cover that a sampling tube may be passed through the cover in order to obtain samples of the oil in the tank.

15 Another object of the invention is to provide guide means adapted to hold the cover in the proper position to slide vertically in the tank without binding and to permit oil to be fed into the tank through the guide means if so desired.

20 Another object of the invention is to construct the guide means that the oil which passes into the tank through the guide means may pass from the guide means close to the bottom of the tank and thereby prevent 25 water which may be in the oil from becoming mixed with the main body of the oil in the tank.

This invention is illustrated in the accompanying drawing, wherein

30 Figure 1 is a vertical sectional view through a tank provided with the improved cover, and

35 Fig. 2 is a horizontal sectional view taken through the tank on the line 2—2 of Fig. 1.

The tank 1 is an ordinary tank such as are commonly used in oil fields for the storage of crude or refined oil. The tank is cylindrical in shape and provided with an outlet valve 2 near its bottom 3. It may 40 be of any height and of any diameter desired and is open at its upper end. When oil is stored in the tanks, there is ordinarily no cover provided and the oil, therefore, rapidly evaporates and further is not only exposed to danger of fire in case a nearby building should catch fire but is also liable to be ignited by lightning. There has, therefore, 45 been provided an improved cover which will serve to protect the oil from evaporation and exposure to fire.

The cover 4 which is of a buoyant construction is formed of heavy sheet metal and provided with a bottom 5, an annular wall 6 and a top 7 which in the preferred form is conical. Tubes 8 and 9 extend vertically 50 through the cover and provide sleeves to re-

ceive hollow guide rods 10. The guide rods 10 are formed of tubing of a length corresponding to approximately the height of the tank and in the preferred form have 60 their lower end portions fitting upon pins 11 which extend upwardly from a base plate 12. The base plate rests upon the bottom 3 of the tank and is of such size that it fits snugly in the tank and practically covers 65 the bottom. By having the base plate cover practically the entire bottom of the tank, it forms a common support for the pins 11 and, therefore, the pins which are rigidly carried thereby will be spaced the proper 70 distance from each other and the guides 10 carried by pins 11 may be readily passed through the sleeves 8 and 9. It should also be noted that, when the tank is emptied and the cover and tubes 10 removed, the plate 75 12 may be drawn upwardly out of the tank and will carry with it sediment which may have accumulated in the bottom of the tank. Oil tanks are nearly all of the same diameter but they vary in height and in order to 80 use the improved cover in connection with a tank having a diameter into which the plate 12 and cover 4 will fit it is merely necessary to provide tubes or pipe 10 of the proper 85 length to extend from the bottom of the tank up to the open upper end of the tank. While there has been shown two guide tubes in the drawing, it will be obvious that additional tubes may be provided if desired.

It will also be obvious that even only two 90 of the pipes or tubes are made use of additional sleeves 8 may be provided in spaced relation to each other about the cover so that the cover will be reinforced and prevented from collapsing. The sleeve 9 instead of passing through the body of the cover is disposed in a well 13 which is formed in the cover so that a sampling tube 95 may be passed through this well and downwardly into the tank in order to remove 100 a sample of oil from the tank. A cover plate 14 is provided for the open upper end of the well 13 and pivotally secured to the upper wall or head of the float by means 105 of a rivet or other suitable fastener 15 which passes through an ear 16 of the cover. A handle 17 is carried by the cover plate so that it may be easily swung into and out of a closed position and a recess 18 is provided in the cover plate so that, when closed, 110 it may fit about the pipe which passes through the sleeve 9.

When the cover is installed, the base plate 12 which carries the pins 11 is first put in place and the pipes 10 will then be passed downwardly in the tank and seated upon the pins. The cover, which is very heavy, will then be engaged by grapples which hook into the handles 19 and the cover lowered into the tank with the pipes passing through the sleeves 8 and 9. Of course, if desired, the cover may be put in place before the pipes, in which case the cover would be lowered so that the pins project through the sleeves and the pipes then put in place. One or all of the pipes will be provided with openings, such as the slots 20, so that oil may pass downwardly through the slotted pipe or pipes and out through the slots 20 into the tank. In the illustration there has been shown only one feed pipe, which is indicated by the numeral 21, and connected with the upper end of the pipe which passes through the sleeve 9 by means of an elbow 22, but it will be obvious that a similar pipe could be connected with the pipe 10 which passes through the sleeve 8. By having the oil fed into the tank through a pipe 10, it is led to a point adjacent the bottom of the tank and, therefore, there will be no splashing of oil and there will be no danger of water which sometimes passes out of a well with the oil becoming thoroughly mixed with the oil in the tank and causing an emulsion to be formed which would render the oil useless. It will also be obvious that, if desired, the cover 14 may be swung to an open position and a feed pipe extended through the well 13 to the bottom of the tank in order to feed oil into the tank. The cover floats upon the surface of the oil in the tank and since it fits snugly in the tank it will cover practically the entire surface of the oil and not only prevent quick evaporation of the oil but also protect the oil from danger of being ignited by fire. While it has been stated that the cover will be used in connection with a tank in which

oil is stored, it will be obvious that it could be used equally well in connection with tanks containing other fluids and prevent them from quickly evaporating or igniting. 50

Having thus described the invention, I claim:

1. A receptacle open at its upper end, a float fitting snugly within said receptacle for vertical sliding movement, a base plate resting upon the bottom of said receptacle, pins extending upwardly from said base plate, and hollow guide bars removably carried by said pins and extending upwardly through said float and provided with outlets 60 adjacent their lower ends. 55

2. A receptacle open at its upper end, a hollow float fitting snugly within said receptacle for vertical sliding movement, said float having its bottom provided with an opening and its head with an opening above the opening in the bottom, a sleeve connecting said openings and providing a well through the float to permit access to the contents of the receptacle beneath the float, guide sleeves passing through said float, one sleeve being located within said well, guide tubes extending upwardly from the bottom of said receptacle and projecting through said guide sleeves, and a cover movably connected with the head of said float and adapted to be moved into and out of closing relation to the upper end of said well. 70 75

3. A receptacle, a float snugly fitting within said receptacle for vertical sliding movement, a base plate resting upon the bottom of said receptacle and covering substantially the entire surface thereof, said plate being removable from the receptacle when the float is removed, and guides all carried by and extending upwardly from said base and projecting through said float to guide sliding movement of the float. 80 85

In testimony whereof I affix my signature.

ALBERT J. HOLT. [L.S.]
